ATTYS.

UNITED STATES PATENT OFFICE.

EDMUND J. BOWEN, OF MAYNARD, OHIO, ASSIGNOR TO THOMAS KELLEY,
OF SAME PLACE.

COKE-OVEN.

SPECIFICATION forming part of Letters Patent No. 315,595, dated April 14, 1885.

Application filed November 6, 1884. (No model.)

To all whom it may concern:

Be it known that I, EDMUND J. BOWEN, a citizen of the United States, residing at Maynard, in the county of Belmont and State of Ohio, have invented certain new and useful Improvements in Coke-Ovens; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

15 This invention relates to coke-ovens; and it consists in the novel construction, combination, and arrangement of parts, as will be more fully described hereinafter.

Referring to the drawings, Figure 1 is a 20 top plan view of my oven. Fig. 2 is a transverse section thereof on line xx , Fig. 1. Fig. 3 is a vertical longitudinal section of same, and Fig. 4 is a detail view of the sectional door.

25 The oven A is open at both ends, and is provided on opposite sides of each end with suitable guides or ways, B, for the gates, presently described. It will be noticed that the oven gradually widens or tapers outward from 30 its front end to its rear or discharge end. This is most clearly shown in Fig. 1. By this construction the discharging of the contents of the oven is facilitated, and clogging of the coke at the rear end of the oven is obviated.

35 Through the roof C of the furnace I form suitable flues or openings, C', preferably five in number, and arranged as most clearly shown in Fig. 1. The floor D of the furnace is by preference inclined downward from one end, 40 in order to facilitate the discharging of the furnace, in the manner presently described. The floor D is provided with a series of rails, E, arranged close together and extended longitudinally along the floor, as clearly shown 45 in Figs. 2 and 3. The object of these rails is twofold. In the first place, they provide suitable ways for the pusher, presently described, and thus prevent all scraping of and damage to the floor. Again, they provide suitable 50 spaces between them in which to place wood,

kindling, &c., which serves to start the fire, and which, when burning, form flues underneath the slack, which operate to carry off the sulphur, &c., and thus facilitate the operation. The gates slide vertically in guides B. 55 One or both of these gates is made in upper and lower sections, F' F'', detachably secured by hooks F³, or in other suitable manner, so that the upper section, F', may be detached from the lower one and raised, so as to permit the leveling of the charge as is desirable. These gates F are usually provided with small openings, as f, to provide the proper circulation for the oven.

In order to conveniently raise the doors F, 65 I provide levers G, pivoted on suitable uprights, G', projected above the oven, and having their short arms connected by chain, or in other suitable manner, with the doors. By depressing the outer ends of the levers G the 70 door will be raised. Such depression may be facilitated by suspending weights G² on the outer ends of the levers, as shown. The pusher H is made a width about equal the narrowest end of the oven, and it is provided 75 with a stem or frame, H', extended horizontally from its rear side. The pushing-lever I is pivoted to the frame H', and has its short end connected by a chain, J, or otherwise with the oven or other suitable support. 80 The point of connection of lever I and chain J forms the fulcrum of the said lever, and in operation it is desirable that the fulcrum be changed at intervals as the charge is being discharged, in order to secure the full advantage 85 of the leverage at all points of operation. To secure this, I preferably connect the chain J with the oven, or if desired with the lever, I by a hook attached to such part, so the links of the chain may be caught thereover. By this 90 construction one link of chain J may be conveniently detached from and another caught over the hook K, so as to shorten the chain from time to time, as may be desirable. It is manifest that this change of fulcrum might be 95 secured in various ways. For instance, the short end of the lever might be secured to one end of a rope, the other end of which would be wound on a drum or windlass which could be given a slight turn from time to time to shorten 100

the rope; or a series of posts might be arranged extending out from the oven, and the lever be pivoted in turn thereon, or by making the lever sufficiently long it might be pivoted permanently; but such arrangement involves a long lever which is in the way and difficult to manage; and I prefer to employ the changing-fulcrum arrangement before described, as by it I make practical the use of a short lever which requires but a small space for its successful operation. The power end of this lever may be operated by man-power; but it is preferably actuated by horse-power hitched to the outer end of the lever and operating to force same toward the oven. In practice I prefer to connect the horse with the lever by a rope or chain, L, and to convey same from the lever forward toward the oven and around a pulley, M, held near said oven, and thence back, as shown, as thereby the horse is arranged distant from and consequently protected from the heat of the furnace and an increase of power and a smoothness of application of such power is attained. I prefer in practice to employ a screw, N, turned through a fixed support, O, in front of frame and arranged to bear against the outer end of such frame. By turning this screw up against the frame the same may be steadily and forcibly moved, so as to easily start the pusher in case same should become clogged by any fusing or other massing of the charge within the oven.

In operation, the pusher is forced through the oven, discharging the same easily and in a short time.

My improvement is a great advance over the common method of discharging coke-ovens, not only on the saving of time, but from the fact that the oven may be discharged when at full heat, so that the oven is left hot to receive the new charge. This new charge being put in the hot oven the slack is instantly ignited, carrying off at once a large quantity of sulphur, &c.

Having thus described my invention, what I claim, and desire to secure by Letters Patent, is—

1. A coke-oven having an inlet-opening at one end and an outlet at its opposite end and having its floor inclined downward toward its discharge or outlet end and provided on such floor with a longitudinal series of rails arranged side by side and a slight distance apart, substantially as set forth.

2. The combination, with a coke-oven, of the pusher, the lever I, and the fulcrum-chain J, whereby the fulcrum of lever I may be set from time to time nearer to the oven and the said lever may be given a movement lateral to the line of motion of the pusher, substantially as set forth.

3. In a coke-oven, the combination of the pusher, the lever I, and the screw N.

In testimony whereof I affix my signature in presence of two witnesses.

EDMUND J. BOWEN.
